UNITED STATES PATENT OFFICE.

GEORGE PEACOCK INNES, OF SYDNEY, NEW SOUTH WALES.

DEVICE FOR HOLDING BOTTLES AND ALLOWING LIQUIDS TO BE WITHDRAWN THEREFROM.

SPECIFICATION forming part of Letters Patent No. 683,768, dated October 1, 1901.

Application filed June 21, 1900. Serial No. 21,106. (No model.)

To all whom it may concern:

Be it known that I, GEORGE PEACOCK INNES, engineer, a subject of the Queen of Great Britain, residing at No. 84 Bathurst street, 5 Sydney, in the British Colony of New South Wales, have invented a new and useful Device for Holding Bottles and Allowing Liquids to be Withdrawn Therefrom, of which the following is a specification.

10 This invention relates to an improved device for holding bottles and allowing liquids to be withdrawn therefrom, and though it has been specially devised for the purpose of enabling the liquid contents under gaseous pressure 15 sure to be safely withdrawn from bottles, either wholly or partially, without affecting the remainder, yet it may be also applied to the holding of bottles containing liquids not under pressure and allowing their contents to be withdrawn.

This improved device for holding bottles and allowing liquids to be withdrawn therefrom consists of an appropriate stand holding a cap or seating for the mouth of the bottle 25 and a bail or staple or yoke, hereinafter termed the "bail," adapted to take around the bottle, the said cap or seating and the said bail revolving together, but eccentrically to one another, on pivots or pintles on said stand or 30 base. Through the cap or seating is a port or passage-way terminating in an appropriate spout and having on the inner end a valve with a spring-stem passing outside of the cap or seating to devices by which it may be operated not only to lift the valve from its seat, but also to remove the stopper (as in the ordinary aerated-water bottle) from its seating. For corked bottles containing liquids not under pressure the valve-stem is a hollow one 35 and the valve has a sharp point, so that it may be thrust through the cork, and the valve-stem is hollow, so that if necessary air or gas may be pumped or supplied through it into the bottle to replace the liquid which flows 40 out.

In order that this invention may be clearly understood, reference will now be made to the drawings herewith, in which—

Figure 1 is a perspective view of an improved device according to this invention, holding a bottle of aerated waters ready for the liquid to be withdrawn therefrom. Fig.

2 is a diagrammatic view of the respective extreme positions of the cap or seating and of the bail. Fig. 3 is a front elevation of this improved device, while Figs. 4 and 5 are side elevations, respectively, when the bottle is being inserted in the device and when the bottle is fixed ready for the liquid to be withdrawn; and Fig. 6 is a sectional elevation of Fig. 5, Fig. 6^a showing the valve-piece in elevation. Fig. 7 is a similar section to Fig. 6, but showing a modified construction of the valve-piece to be used for a corked bottle; and Fig. 8 is an exaggerated cross-section of the valve, the port or passage, and the valve-stem.

A stand or base 1, which may be of any more or less ornamental design and of any appropriate material, has cheeks 2, each of which has a jaw or bearing 3 and a pintle 4. In the jaw or bearing 3 is pivoted the cap or seating 5, containing layers of packing 6 of, say, india-rubber or other elastic or semi-elastic material. Through and to this cap or seating is screwed the valve-piece 7, on which is the valve 8, having a stem 9 passing through the port or passage 10 and through the stuffing-box 11 to a footpiece 12. This stem 9 has a spring 13 placed between said footpiece 12 and the nut 14 of the stuffing-box 11. From the port or way 10 there protrudes a spout or discharge-bend 15. Under the foot 12 is a recess in which takes the ball 16 of the inner end of the thumb-lever 17, having a thrust-spring 18 thereunder. One of the pivots of the seating 5 has a square 19 thereon, around which takes a connecting-piece 20. Around the pintles 4 take the inner ends 21 of the bail 22, the outer end 23 of which contains a female screw 24, through which passes the male screw 25, whose inner end is fastened to or runs in a cap or plate end 26. The connecting-piece 20 reaches from the square 19 on the cap or seating 5 upwardly to one of the bail sides 22, so that radial motion of the bail will be communicated to and be partaken of by the cap or seating 5.

In operation the bail and the seating are in the positions as shown in Fig. 4, or what may be termed their "lower" positions. The bottle—say an aerated-water bottle—is then placed within the bail 22, with its mouth on the packing 6 of seating 5 and its bottom against

the cap 26, the screw 25 being revolved until there is a loose grip upon said bottle. The bottle and the bail 22, carrying with it the cap or seating 5, (by means of the connection 5 20,) is then elevated into the position shown in Figs. 1, 3, 5, and 6, the bottle being inverted. The eccentricity of movement of the bail and of the seating causes the bail to draw the bottle - mouth firmly and hardly 10 against the packing 6 in the seating 5 and to take a very firm grip of the bottle while making an air and water tight connection around the mouth of the inverted bottle, and at the same time the valve-head pushes or eases the 15 stopper 27 back from its seat. Now to withdraw the liquid wholly or in part the thumb or fingers are placed upon lever 17, which elevates the valve-stem 9, raising the valve 8 from its seat and further lifting the ball or 20 stopper 27 from its seat in the bottle, thereby enabling the liquid to pass into the port or way 10 and thence through the spout 15 into a receptacle placed to receive it. When sufficient liquid for the immediate purpose 25 has been withdrawn, the pressure on the thumb-lever 17 is withdrawn, when the valve 8 immediately returns to its seat and makes a tight joint thereon, preventing the escape of water or gas from the bottle. Similar partial 30 withdrawals may be continued until the whole of the contents are withdrawn, when the bottle is released by forcing it and the bail and the seating 5 backwardly to the lower position, when the bottle may be removed and 35 another one put in its place to have its contents withdrawn in part as before or wholly. The screw 25 and the cap 26 enable the joint on the bottle - mouth to be made as tight as desired and also allow for the differences in length of various bottles which 40 may be used.

The modification shown in Figs. 7 and 8 is for use with bottles which are corked and in which the contents are under pressure and 45 with corked bottles in which the contents are not under pressure. In this construction the valve-piece 7 is elongated for some distance, so that it will protrude through any ordinary cork in a bottle. The valve 8 is made with 50 a sharp point, and its stem 9 of course is lengthened to the necessary extent. In other respects the parts are the same as those hereinbefore described. With these modified parts liquid under pressure, such as champagne, may be withdrawn wholly or partially 55 from corked bottles, it being only necessary to have the screw 25 of sufficient length to enable the bottle to be forced onto the seating 5 with the elongated stem of the valve-piece 7 and the valve passing through the cork.

Should it be desired to use this device to withdraw liquids which are not under pressure, then the valve-stem 9 would be made 60 hollow and there would be passages 28 in it and in the valve itself. On the base of the valve-piece would be provided a nipple or

union-piece 29, on which to secure the end of a pipe from an air pump or chamber or from a gas-charging apparatus. To withdraw the 70 liquid, it would then be necessary to open the valve by means of the thumb-lever 17 and to force air or gas into the bottle through the passage 28 in the hollow valve-stem 9 and in the valve 8 to replace the contents which 75 will flow out through the passage 10 and spout 15.

Having now particularly described and ascertained the nature of this said invention and in what manner the same is to be performed, I declare that what I claim is—

1. The combination with a stand provided with a pair of cheeks having forked ends, of a bail pivotally secured to said cheeks and carrying a screw-cap in its upper end, a cap 85 5 pivotally connected to the forked ends of said cheeks and provided with a series of layers of packing material, a cylindrical tube extending through said cap 5 and packing material and connected to a discharge-spout, 90 and a valve mechanism arranged in suitable relation to the said tube, substantially as described.

2. The combination with a stand provided with a pair of cheeks having forked ends, of 95 a bail pivotally secured to said cheeks and carrying a screw-cap in its upper end, a cap 5 pivotally connected to the forked ends of said cheeks and provided with a series of layers of packing material, a cylindrical tube 100 extending through said cap 5 and packing material and connected to a discharge-spout, a valve adapted to be normally seated against the upper end of said tube, a valve-stem secured thereto and extending through the said 105 tube and suitable operating mechanism connected to said stem, substantially as described.

3. The combination with a stand provided with a pair of cheeks having forked ends, of 110 a bail pivotally secured to said cheeks and carrying a screw-cap in its upper end, a cap 5 pivotally connected to the forked ends of said cheeks and provided with a series of layers of packing material, a cylindrical tube 115 extending through said cap 5 and packing material and connected to a discharge-spout, a valve adapted to be normally seated against the upper end of said tube, a valve-stem secured thereto, a footpiece secured to the lower 120 end of said stem, a coil-spring mounted upon said stem between the end of said casing and footpiece, and a spring-pressed lever suitably connected to said footpiece; substantially as described.

4. The combination with a stand, of a bail pivotally connected thereto, a screw fastening-cap carried by said bail, a cap 5 pivotally connected to said stand and provided with a suitable packing, the said caps adapted to 125 retain a bottle in position when arranged within said bail, a valve mechanism connected to said stand and suitably operating through said cap 5 and packing, and a suit-

able connection between said cap 5 and said bail, substantially as described.

5. The combination with a stand, of a bail connected thereto, a fastening-cap carried by said bail, a cap 5 connected to the stand, the said caps adapted to retain a bottle in position when arranged within said bail, a valve mechanism connected to the stand and operating through the cap 5 and a suitable connection between cap 5 and the bail.

10. In a device of the character described, the combination with a stand, of a cap connected thereto, a bail pivotally connected to the stand and adapted to secure a bottle to said cap and a valve mechanism connected to the stand and adapted to extend into the bottle.

15. In a device of the character described, a

cap connected to a suitable support and provided with a passage, a bail carried by the 20 support for securing a bottle to the cap and a valve mechanism adapted to extend through said passage.

25. In a device of the character described, a bail, a cap carried thereby, a cap 5 provided with a passage, a valve mechanism adapted to extend through said passage for closing the same, and means for operating said valve mechanism.

In testimony whereof I have signed my 30 name to this specification in the presence of two subscribing witnesses.
